UNITED STATES PATENT OFFICE.

JACOB J. NICHOLS AND WILLIAM S. McLEWEE, OF NEW YORK, N. Y.,
ASSIGNORS TO BRADLEY & HUBBARD MANUFACTURING COMPANY,
OF WEST MERIDEN, CONN.

DESIGN FOR A LAMP-FOUNT.

SPECIFICATION forming part of Design No. 11,940, dated August 10, 1880.

Application filed June 9, 1880. Term of patent 7 years.

To all whom it may concern:

Be it known that we, JACOB J. NICHOLS and WM. S. McLEWEE, of New York, in the county of New York and State of New York, 5 have invented a new Design for Lamp-Fount; and we do hereby declare the following, when taken in connection with the accompanying drawings and the letters of reference marked thereon, to be a full, clear, and exact description of the same, and which said drawings constitute part of this specification, and represent, in—

Figure 1, a top view; Fig. 2, side view.

This invention relates to a design for lamp-15 fount; and it consists in the shape of the fount, as shown in the accompanying illustrations.

In horizontal plane the fount is square, as seen in Fig. 1, contracting from the top to the bottom, thus making a shape in form of an inverted frustum of a pyramid. The angles are 20 slightly rounded, as shown, and the fount is provided with collar attachment at the top and socket attachment at the bottom.

We claim—

The design for lamp-fount, substantially as 25 shown and described.

J. J. NICHOLS.
W. S. McLEWEE.
